T. RIGBY

METHOD FOR MAKING GUTTER ENDS

Original Filed May 25, 1922

WITNESS:

Bob Pritchel

FIG. 5.

INVENTOR

Thomas Rigby

by
Frank S. Busser
ATTORNEY.

UNITED STATES PATENT OFFICE.

THOMAS RIGBY, OF PHILADELPHIA, PENNSYLVANIA, ASSIGNOR TO BERGER BROS. COMPANY, OF PHILADELPHIA, PENNSYLVANIA, A CORPORATION OF PENNSYLVANIA.

METHOD FOR MAKING GUTTER ENDS.

Original application filed May 25, 1922, Serial No. 563,626. Divided and this application filed December 4, 1922. Serial No. 604,720.

To all whom it may concern:

Be it known that I, THOMAS RIGBY, a citizen of the United States, residing at Philadelphia, county of Philadelphia, and State of Pennsylvania, have invented a new and useful Improvement in Methods for Making Gutter Ends, of which the following is a full, clear, and exact description, reference being had to the accompanying drawings, which form a part of this specification.

This invention relates to a method of making gutter ends, or ends for eaves troughs.

The object of my invention is to provide a method for making ends of this character which are uniform, which can readily be applied to the ends of troughs or gutters without first separating the trough receiving elements, and which may be driven into position to form tight joints without soldering.

The precise nature of my invention will best be understood by reference to the accompanying drawings in which is illustrated a gutter end made in accordance with my invention and views illustrative of various steps in its production, it being understood that various changes may be made without departing from the spirit of my invention as defined in the appended claims.

Fig. 1 is a perspective view of one form of end made in accordance with my invention.

Fig. 2 is a plain view thereof.

Fig. 3 is a sectional view on the line 3—3 of Fig. 2.

Fig. 4 is a view, similar to Fig. 2, showing a gutter end, in position on a trough.

Fig. 5 is an end view thereof with the trough in sections.

Fig. 6 diagrammatically illustrates the various steps in the formation of the ends.

The gutter end shown in the drawings comprises an end member *a* of semi-cylindrical form, having an integral arcuate flange *b*, slightly flared. The gutter end is also provided with an inner arcuate flange member *c* adjacent to the flange *b*. This flange member *c* is secured in position by a radially disposed flange along one edge thereof which is secured within an arcuate bead *d* formed of members extending from the end *a* and flange *b*. The flange member *c* is substantially normal to the end *a*, while the outer portion of flange member *b* extends at an angle thereto, so as to form a

tapered recess between the flange members *b* and *c*, as clearly shown in Figs. 1, 2 and 3. 55

I preferably form the flange member *c* normal to the end member *a*, as well as somewhat longer than the flange member *b*.

This facilitates the application of the device to the end of a trough, and also causes the flange member *c* and trough to lie parallel to each other when the end is driven home on the end of a trough.

When applying a gutter end to a gutter or trough which has been previously 65 shaped as shown at *e* in Figs. 4 and 5, the end of flange member *c*, which extends beyond member *b* is laid within the trough, and the trough end is pushed longitudinally, relative to the trough, until the trough is 70 well seated between flange members *b* and *c*.

The trough end is then gently tapped along the bead *d* to firmly wedge the end of the trough *e* between the flange members *b* and *c*. As the flange member *c* is parallel to 75 the trough *e* and the inner face of the trough is forced against the outer face of flange member *c* by the wedging action, a watertight joint will be formed between these faces, without soldering. 80

When it is desired to remove an end or replace an end with a new end, the end can readily be removed from the trough by tapping, without injury to either the end or trough. 85

In the manufacture of the ends such as shown, blanks of substantially semi-cylindrical form are first died out, a section of a portion of one being shown at *f* in Fig. 6. The blanks are then placed between dies to 90 form a deep arcuate flange thereon as shown at *g* in Fig. 6. The flanged blanks are then placed between drawing dies and an arcuate bead is formed, with an arcuate recess between the bead forming members as shown 95 at *h* in Fig. 6. The beaded blanks together with narrow strips of sheet metal are assembled as shown at *i* in Fig. 6, and are assembled in dies such as shown in Fig. 7. The dies are then closed about the assembled blanks to roll the bead inwardly and bend a flange on the inserted strip, which forms flange *c* and secures said flange in position as shown at *j* in Fig. 5, and thus completing the article as shown in Figs. 1-3. 100

The advantages of my invention result

from the provision of a method of forming gutter end having two flanges extending therefrom, arranged to receive the end of an eaves trough or gutter between them, one 5 of the flanges extending at an acute angle to the other whereby a tapered recess is formed to permit wedging the trough between them and form a tight joint without the use of solder, and in which the mouth 10 of the recess is of sufficient width to readily permit the entrance of the trough.

This application is a division of my application Serial No. 563,626, filed May 25, 1922.

15 Having now fully described my invention, what I claim and desire to protect by Letters Patent is:

1. The method of making gutter ends having an end member and two flanges extending at substantially right angles thereto with a flared gutter receiving space between them, comprising assembling partially shaped gutter end forming members, maintaining the outer free ends of the flange 20 forming members spaced from each other and simultaneously forming a bead at the junction of the end member and the flanges, and forcing the flanges into engagement with each other adjacent to the bead to 25 form a tapered groove between the flanges.

2. The method of making gutter ends having two flanges extending from an end member, with a tapered recess between the

flanges, comprising the steps of assembling a flanged blank and a flange forming strip, 35 forming a bead at the junction of the flange and the end forming portion of the flanged blank and simultaneously folding within the bead one edge of the strip, and during the forming of the bead maintaining the free 40 edges of the flanges separated to form a tapered recess simultaneously with the bead- ing.

3. The method of making gutter ends of semi-circular form having two arcuate 45 flanges extending therefrom with a flared recess between them, comprising the steps of forming a blank with a semi-circular end member, an arcuate flange extending from the arcuate peripheral portion thereof and 50 an arcuate groove in a bead between the flange and the body, placing an edge portion of a flange forming strip in said groove, holding the other edge portion of the said positioned flange forming strip free 55 of the outer portion of the flange, and simultaneously rolling over a bead and forcing the flange forming member and flange into engagement with each other adjacent to the end member while holding the free edge portions of the flange and flange forming strip separated.

In testimony of which invention, I have hereunto set my hand, at Philadelphia, Pa., on this 29th day of November, 1922.

THOMAS RIGBY.
